UNITED STATES PATENT OFFICE.

NELLIE RUTH VIDAVER, OF NEW YORK, N. Y.

DESIGN FOR A PETTICOAT.

50,489.

Specification for Design. Patented Mar. 20, 1917.

Application filed January 6, 1917. Serial No. 141,051. Term of patent 3½ years.

To all whom it may concern:

Be it known that I, NELLIE RUTH VIDAVER, a citizen of the United States, residing at New York, in the county of New York and State of New York, have invented a new, original, and ornamental Design for Petticoats, of which the following is a specification, reference being had to the accompanying drawing, forming part thereof.

The figure is a front elevation of a petticoat, showing my new design.

I claim:

The ornamental design for a petticoat, as shown.

NELLIE RUTH VIDAVER.
